(57) **CLAIM**

What is claimed is the ornamental design for a guidewire hoop design, as shown and described.

DESCRIPTION

FIG. 1 is a perspective view of a guidewire hoop design of my new design;

FIG. 2 is a top view of the embodiment of FIG. 1; and, FIG. 3 is a bottom view of the embodiment of FIG. 1.

The broken line showing of environment in the drawings is for illustrative purposes only and forms no part of the claimed design.
